Original application December 21, 1933, Serial No.
703,370. Divided and this application February
13, 1937, Serial No. 125,550

9 Claims. (Cl. 271—62)

This invention relates to improvements in sheet feeders for high speed printing presses and kindred machinery and refers particularly to pile feeders wherein the sheets are picked off the top of a pile and are fed into the printing press or other machine with which the feeder is connected.

As in the copending application of Elmer W. Belluche and Frank R. Belluche, Serial No. 703,370, filed December 21, 1933, of which this is a division, it is a general object of the present invention to effect an all-around improvement in feeders of this type.

A special object of this invention is to provide novel means for rapidly elevating or depressing the pile and automatic means for insuring the presence of the operator directly at the piles so as to preclude the possibility of raising or lowering the pile too far without the use of complicated and not entirely reliable safety devices. Heretofore, the provision of an independent drive for the pile elevator, operable to raise and lower the pile under manual control, has been a more or less complicated mechanism and has required the disconnection of several driving connections or the complete shutting down of the feeder drive. Also in past constructions, special safety devices had to be provided to preclude too great an elevation or depression of the pile.

These deficiencies and objections of past feeder constructions are overcome in the present invention by the provision of a readily operable gear shifting arrangement and means responsive to the actuation of the control member therefor, for requiring manual depression of the electric starting button as long as elevation or depression of the pile is to continue.

Another object of this invention is to provide simple means for effecting sidewise adjustment of the pile to insure proper disposition of the pile with respect to the delivery mechanism.

A further object of this invention is to so construct the feeder as to facilitate its erection. Heretofore, it has always been a difficult task to erect a feeder of the character described particularly where it is designed to handle comparatively large sheets. In the absence of hoisting equipment which in the average printing shop is not available, the erection of the feeder has entailed manual lifting of heavy mechanisms into comparatively high positions and the difficult securing of such mechanisms to their supporting structure, while so held.

To overcome this objection, the present invention contemplates the construction of the sup-

porting structure and the main mechanism head which is the heaviest portion of the device to be elevated, so that part of the pile elevator may be employed to raise the mechanism head to its proper position, and to hold the same while it is secured in place.

With the above and other objects in view which will appear as the description proceeds, our invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawings illustrate one complete example of the physical embodiment of the invention constructed according to the best mode so far devised for the practical application of the principles thereof, and in which:

Figure 1 is a side view (feed side) of a sheet feeder constructed in accordance with this invention;

Figure 2 is an enlarged view in elevation of the feed side of the mechanism head;

Figure 3 is a section view taken through Figure 4 on the plane of the line 3—3;

Figure 4 is a section view through the feeder taken on the plane of the line 4—4 of Figure 1;

Figure 5 is a detail view showing the power drive means for the pile raising and lowering mechanism;

Figure 6 is a detail view partly in section taken on the plane of the line 6—6 of Figure 5;

Figure 7 is a view similar to Figure 6, but illustrating the elements thereof in another position;

Figure 8 is a detail perspective view showing the barrier against which the pile rests and illustrating the manner of adjusting the pile sidewise;

Figure 9 is a detail section view taken on the plane of the line 9—9 of Figure 8;

Figure 10 is a detail section view taken through Figure 4 on the plane of the line 10—10 and showing the pile feeler;

Figure 11 is a view showing part of the supporting structure and illustrating the manner of raising the mechanism head;

Figure 12 illustrates the manner of raising the pump supporting shelf; and

Figure 13 is an electrical diagram illustrating the control for the pile raising and lowering power drive.

Referring now particularly to the accompanying drawings in which like numerals indicate like parts throughout the several views, it will be seen

that the general arrangement of the feeder comprises a supporting frame A, a mechanism head B mounted on the supporting frame, an elevator C suspended from the supporting frame 5 for the pile of sheets P, front and rear suckers D and E, respectively, to pick off the topmost sheet, and a delivery mechanism F to receive the sheet as it is forwarded by the front suckers, and convey it to a printing press, folder, or other machine 10 with which the feeder is connected.

Supporting frame

The general support for the feeder consists of four upright posts or columns, two front columns 15 6 and two rear columns 7. The bases of these columns rest on the floor and are preferably secured thereto, and the tops carry caps 8 on the front columns and 9 on the rear columns. The two front columns are connected at their tops 20 by a tie rod 10 anchored at its opposite ends to the front caps 8 and the rear posts are connected across their tops by a tie rod 11 having its opposite ends anchored in the caps 9.

The front and rear posts are rigidly connected 25 by longitudinal tie rods 12, whose ends are anchored in the front and rear column caps. The transverse and longitudinal tie rods thus form a rigid frame connecting the upper ends of the columns.

30 The front and rear column caps are further rigidly connected by rack bars 13 whose opposite ends are fixed thereto.

Pile support and associated mechanism

35 The pile elevating and supporting means consists of two longitudinal rails 14 supported by chains 15 trained over sprockets 16 fixed to longitudinal shafts 17, which are journalled in open topped bearings in the front and rear column 40 caps. One end of each chain is attached to one end of one of the rails 14 and the opposite ends of the chains hang down into the inside of the hollow columns.

Supported on the rails 14, which are inclined 45 forwardly, is a platform 18 upon which the pile of sheets rests. The platform 18 has transverse supporting beams 19' provided with rollers 19 to track on the rails 14 and thus support the platform for forward and backward movement.

50 The forward ends of the shafts 17 have worm wheels 17' secured thereto and meshing with the worm wheels are right and left handed worms 20' carried by a shaft 20 which extends transversely across the tops of the front columns, being journalled in open topped bearings formed as part 55 of the front column caps 8. Obviously, the engagement of the worm wheels with the worms precludes rotation of the shafts 17 by the weight of the pile, and rotation of the worm shaft 20 provides means for adjusting the elevation of the pile.

The worm shaft 20 is adapted to be driven rapidly by manually controlled means to effect rapid elevation or depression of the pile, and is 60 also arranged to be automatically actuated during the operation of the feeder to gradually raise the elevation of the pile as the sheets are removed therefrom. The manner in which the shaft 20 is actuated will be hereinafter described.

70 In view of the inclination of the supporting rails 14, the platform and the pile supported thereon automatically moves forwardly to maintain the front face of the pile against a barrier 21. The barrier 21 as best illustrated in Figure 8, 75 consists of a plurality of intermediate vertical

bars 22 between two endmost vertical bars 23. The upper ends of the intermediate bars are all attached to a cross piece 24 which forms a support for the sheets as they are forwarded from the pile into the delivery mechanism.

The endmost bars 23 are rigidly connected at their lower portions by diagonal cross braces 25, and near their upper portions by a transverse bar 26. At their extreme bottom, the endmost bars are transversely slidably mounted on a suitable transverse support (not shown) carried by the front columns. The cross bar 26 connecting the upper portions of the endmost vertical bars 23, is slidably mounted on a shelf 27 carried by the front columns, as will be hereinafter more 15 fully described, and is slideable by means of an adjusting mechanism 28 (see Figure 8) to effect sidewise adjustment of the bars 23.

The adjusting mechanism 28 comprises a screw 29 having a hand wheel 30, and a medially pivoted 20 lever 31 carrying a nut at one end threaded on the screw 29 and having a connection 32 at its opposite end with the transverse bar 26.

The transverse adjustment of the side bars 23 is utilized to effect sidewise adjustment of the 25 pile with respect to the delivery mechanism, and to this end, the connections between the front chains and the front ends of the rails 14 embody slides 33. These slides 33 embrace the bars 23 and are attached to side plates 34 which form 30 parts of the connections between the ends of the chains and the rails.

Mechanism head

The mechanism head B is supported on the 35 front columns. Its supporting structure comprises two side frames, a gear side frame (not shown), and a feed side frame 41 connected by transverse tie rods 42, 43 and 4, and by a rectangular cross bar 45.

This rigid framework is suspended from the front column caps by bolts 46 passing through aligned openings in flanges 47 carried by the column caps and the adjacent upper inner corner portions of the side frames, (see Figure 3). 45 While the drawings show only the feed-side frame 41 of the mechanism head, this being sufficient for a disclosure of the invention here involved, it is desired to note that in many respects the two side frames are alike. This is especially 50 so as to the manner of attaching the side frames to the front column caps.

Each side frame has a recess 48 extending upwardly from its bottom to divide the lower portion thereof into front and rear leg portions 49 and 50, respectively. The rear leg portions 50 of the side frames lie adjacent the front columns and are clamped thereto by U straps 51.

To provide anchorage for the ends of the straps, the side frame leg portions 50 carry transverse 60 stub shafts 52 which project from opposite sides of the side frames. Adjusting screws (not shown) may be threaded into these transverse stub shafts to bear against the adjacent portions of the columns and provide convenient means for adjusting 65 the position of the mechanism head.

A main cam shaft 57 is supported from the side frames with its axis located in the crotch of the recesses 48, by bearings fixed to the inner faces of the side frames. Suitable mechanism 70 (not shown) drives the cam shaft, and as described in the aforesaid copending application, the main drive for the feeder is preferably taken from the press or other machine which it feeds.

Extending across the space between the side 75

frames is a main delivery roll 58 driven from the cam shaft and located juxtapose the forward edge of the top cross piece 24 of the barrier 21, so that as the sheets are carried forward by the front suckers, their leading edge portions will be deposited on the roll. Tapes 59 are trained about the roll to be driven thereby and to carry the sheet forward into the delivery mechanism.

The cam shaft 57 has a plurality of cams mounted thereon, most of which are associated with mechanism not essential to a disclosure of the invention here involved. One of these cams, however, forms part of the mechanism for elevating the pile. This cam 60 has two functions related to the operation of the automatic pile elevator. It continuously drives the means for turning the worm shaft 20, and also initiates the functioning of the worm shaft driving means. For carrying out its first function, a crank pin 61 is fixed thereto. Attached to the pin 61 is a pitman 62 to oscillate a pawl carrier 63, pivotally mounted on the adjacent end of the worm shaft 20. Between the pawl carrier 63 and the outer end of the adjacent bearing for the shaft 20 which forms part of the column cap, is a sprocket wheel 64, and a ratchet wheel 65, the ratchet wheel being directly adjacent the pawl carrier. Both the ratchet wheel and the sprocket are fixed to the worm shaft 20.

A pawl 66 is pivotally mounted as at 67 from the pawl carrier to lie above the ratchet wheel and engage the same, when permitted by a mask 68. The mask 68 is formed by the outer curved end portion of a lever 69 pivotally mounted as at 70 from the adjacent rack bar 13, and provides a track on which a roller 71 carried by the free end of the pawl rides. In its operative raised position, the mask is so disposed with respect to the center of the shaft 20 as to hold the pawl out of engagement with the ratchet wheel, but upon dropping out of the way, permits engagement of the pawl with the ratchet wheel.

Inasmuch as the main cam shaft 57 and consequently the cam 60 is continuously turning, it follows that the pawl carrier 63 and the pawl are constantly being oscillated. Normally, the oscillation of the pawl has no driving effect upon the shaft 20, but under certain conditions, as determined by the height of the pile, the mask drops out of the way and permits momentary engagement of the pawl with the ratchet wheel so as to turn the shaft 20 a slight distance and elevate the pile to its proper height.

The control for the mask 68 incorporates the cam 60 in the following manner: Tracking on the cam 60 is a follower 72 carried by one end of a lever 73, which is medially pivoted as at 74. The opposite end of the lever 73 has a tension spring 75 connected thereto which yieldably tends to cause the roller 71 to track the cam 60. Also connected to said opposite end of the lever 73 is a link 76, which extends upwardly to connect with one arm of a bell crank lever 77.

The bell crank lever 77 is fixed to a shaft 78 extending transversely from the feed side inwardly to a bracket 79 adjustably mounted in the center of the feeder. Fixed to the shaft 78, adjacent the bracket 79, is a curved lever arm 80 (see Figure 10) which overhangs the adjacent portion of the pile and carries a pile feeler 81 at its outer free end. The lower end of the pile feeler has a roller 82, which is adapted to engage the top of the pile, and a link 83 connected with the medial portion of the feeler and receiving support from the bracket 79, serves to hold the feeler

in a substantially vertical position as it is raised and lowered by oscillation of the shaft 78. Oscillation of the shaft 78 is produced by the motion of the lever 73 in following the cam 60, which is merely a round disc having a flat portion, the spring 75 pulling the link 76 down to turn the shaft 78 in one direction whenever the flat portion of the cam aligns with the roller 72.

The direction of rotation imparted to the shaft 78 by the spring 75 is such as to engage the feeler 10 with the top of the pile so that the force which causes the feeler to move down onto the pile is not positive but yieldable. Consequently, the degree of rotation which it is possible to impart to the shaft 78 in consequence to the tendency 15 of the spring 75 to cause the cam follower 72 to follow the flat portion of the cam 60, is limited and determined by the height of the pile. As the sheets are removed from the pile, the degree of possible rotation of the shaft 78 increases and 20 when a predetermined maximum degree of rotation is permitted, the bell crank lever 77, through an adjustable stop 84, moves a lever 85 to lift a latch bar 86 out of operative position.

The lever 85 is pivotally mounted on the feed 25 side front column cap as at 87 and the latch bar 86 is carried directly by the lever 85. The outer end of the latch bar 86 is notched to define a sharp shoulder 88, with which, when the latch bar is in operative position, a stud 89 carried by the arm 90 of the bell crank lever 69 engages.

In its normal operative position, the latch bar 86 holds the bell crank lever 69 in its position maintaining the mask 68 in its raised or active 35 position, but when the latch bar 86 is lifted out of engagement with the stud 89, the lever 69 turns by gravity about its pivotal mounting 70, and permits the operative engagement of the pawl with the ratchet wheel, whereupon the next 40 successive forward stroke of the pawl turns the worm shaft a slight degree to elevate the pile back to its proper height.

To reset the mask, the oscillation of the pawl carrier is imparted to the lever 69 through a link 45 91. One end of the link 91 is connected to a short lever 92 forming part of the pawl carrier and the opposite end of the link is slidably in a stud carried by a downward extension 93 of the lever 69.

A collar 94 on said last mentioned end of the link serves to lift the lever 69 and the mask carried thereby to its raised position and sufficiently far to re-engage the stud 89 with the latch bar 86. Thereafter, the oscillation of the 55 pawl carrier 63 merely reciprocates the rod 91 with respect to the stud carried by the lever extension 93 without having any effect thereon until the latch bar 86 is again tripped as a result of the lowering of the pile top.

Through the mechanism described, rotation is imparted to the worm shaft 20 whenever the height of the pile drops slightly, and as the worm shaft directly actuates the shafts 17 on which the sprockets 16 are mounted, the pile supporting 65 chains are lifted to bring the pile height to its required elevation.

Independent manually controlled pile elevator

Power driven mechanism is provided for rapidly elevating or lowering the pile or its carrying platform. This mechanism is manually controlled and functions entirely independent of the automatic pile elevator just described. It is driven at the will of the operator, in either direc- 75

tion, from a pinion 95 fixed to the outer end of a jack shaft 96. The jack shaft 96 is driven from a motor 97 mounted on shelf 27 and drives the pumps (not shown). By engaging either of two meshing gears 98 or 99 with the pinion 95, the pile is caused to raise or lower. The gears 98 and 99 are carried by a lever member 100 pivotally mounted on a stub shaft 101 journaled in a suitable bearing carried by a standard 102 which also provides a bearing for the adjacent end of the jack shaft 96.

In the normal neutral position of the lever member 100 neither one of the gears 98 or 99 meshes with the pinion 95, but upon clockwise movement of the lever member about the axis of the stub shaft 101 by means of its handle 103, the gear 98 is meshed with the pinion 95 to drive a large gear 104 fixed to the shaft 101 in a counterclockwise direction as viewed from the feed side of the feeder (see Figure 5).

Also fixed to the shaft 101 is a sprocket wheel 105, which upon rotation of the shaft through the gear connection just established, transmits a like rotation to the sprocket 64 fixed to the worm shaft 20 through the medium of a sprocket chain 106. This counterclockwise rotation of the worm shaft 20 imparts rotation to the shafts 17 in a direction to raise the pile.

To lower the pile, the lever member 100 is swung to its opposite position meshing the gear 99 with the pinion 95 so that the gear 99 acts as an idler and changes the direction of rotation of the gear 104. The lever member 100 is normally held in its neutral position by a releasable lock comprising a screw 107 threaded in the adjacent wall of the standard 102 and having a head 108 adapted to enter a counterbore 109 formed in the lower end portion 110 of the lever member. A hand wheel 111 on the outer end of the screw provides means for disengaging the head 108 from the counterbore to release the lever member for movement into either of its operative positions, the lower end portion 110 of the lever member having an arcuate slot 112 to accommodate the screw 107.

At the opposite ends of the arcuate slot there are counterbores 113 and 114 in which the head 108 of the screw may be engaged to secure the lever member in either of its positions to effect either descent or elevation of the pile.

Directly associated with the lock screw for holding the lever 100 in any of its three positions, is means to positively render the automatic pile elevating mechanism inoperative. This means comprises a lever 115 medially pivotally mounted as at 116, and having one end 117 bored to receive the lower end of a push rod 118, the upper end of which is attached to the mask carrying lever 68. A collar 119 is fixed to the lower end portion of the rod 118 to be engaged by the end 117 of the lever 115 in the event the mask lever is down and the lever 115 is actuated in a manner now about to be described.

A lug 120 is formed on the end of the lever 115 opposite its connection with the rod 118. This lug, as best illustrated in Figures 6 and 7, lies in the path of the screw head 108 as the screw is turned to withdraw the head out of any one of the counterbores in which it may be engaged so that upon such outward axial movement of the screw, the lever 115 will be moved about its pivotal mounting to elevate its end 117 and consequently the mask lever if it happens to be in its lowermost inoperative position.

The lower end portion 110 of the lever member

100, which is circumferential to the axis of the shaft 101, also has two outwardly projecting lugs 121 adapted to engage a rounded projection 122 on the lever 115 upon movement of the lever member 100 out of its normal neutral position, to depress the adjacent end of the lever 115 and hold the same down after the screw head 108 is moved out of engagement with the lug 120.

The rocking movement of the lever 115, as described, besides serving to lift the mask lever in the event this member is in its lowermost inoperative position, also has an additional safety function, as now about to be described.

As stated, the drive for the rapid pile elevating and lowering means is obtained from the pump drive jack shaft, which in turn is driven from the motor 97. The starting and stopping of the motor is controlled by a push button control box 123 of conventional construction. As is customary, in push button controls of this character, a "start" button 124, and a "stop" button 125 are provided.

As illustrated in the electrical diagram in Figure 13, depression of the start button 124 when the stop switch is in its normally closed position, completes a circuit which energizes the coil of a relay R, whose switches S¹ and S² then close to connect the power lines L¹ and L² with the motor. The relay R also has an auxiliary holding switch S³ connected in series with the normally closed stop switch 125, which closes to maintain the relay energized after opening of the start switch. Thus the motor will continue to run until the stop button is depressed opening the stop switch and breaking the holding circuit.

Mechanically connected to and closing with the start switch 124 is another switch 124'. This switch is connected in series with the start switch 124 so that when the stop button is held down holding the stop switch open, the motor may be operated but only by depressing and holding the start switch closed.

Consequently, with the "stop" button held down, it is possible to use the "start" button of the control box as an "inching" control with the motor operating only as long as the "start" button is held down. This feature is utilized to insure the operator's presence at the pile end of the feeder during the actual raising and lowering of the pile.

To this end the control box 123 is mounted in such a position that the depressible end 126 of the lever 115 is directly over the "stop" button 125. Hence, when the lever 100 is shifted into either of its operative positions, the "stop" button of the switch control box will be depressed to stop the drive motor 97 if this motor is in operation. As long as the lever member is in either shifted position, the motor can be operated only by holding the "start" button 124 down and as the control box 123 is so located that the operator can readily observe the position of the pile, it is highly improbable that the pile will be raised or lowered too far.

Method of erection

The construction of the feeder and particularly the mechanism head and its support facilitates the erection of the feeder. This feature of the feeder is particularly desirable especially where the feeder is designed to handle comparatively large sheets for in such structures, the operating parts, which must be mounted at the top of the supporting structure are quite heavy.

In the present structure, the mechanism head may be completely assembled by the manufac-

turer, and then shipped and raised into position entirely without the aid of hoists and with a minimum of help and labor.

The method of raising the mechanism head to its proper position at the top of the front columns is illustrated in Figure 11. As here shown, the general supporting frame comprising the columns and the connecting members at the upper ends thereof, has been set up and likewise the pile 10 elevating chains and the sprocket shafts with the sprockets over which they are trained, are in position.

Attached to the lower ends of the front chains are carrier brackets 130. These brackets have 15 rollers 131 to engage the front and rear faces of the columns and slidably mount the carriers for vertical movement. The lower ends of the carriers are provided with hooks 132 adapted to engage the stub shafts 52 on the mechanism head 20 and thus support the entire head. To hold the head on the carrier brackets, retaining hooks 133 are provided, the hooked ends thereof engaging over the tie rod 42. The opposite ends of the retaining hooks are slidably received in studs 134 fixed to the carrier brackets and are threaded to receive wing nuts 135 by which the angular position of the head with respect to the columns is readily adjustable.

With the carrier brackets lowered, the mechanism head may be readily mounted thereon as to do so requires very little, if any, lifting. The mechanism head having been properly mounted on the carrier brackets, the worm shaft 20 is manually actuated by means of a crank 136 temporarily attached thereto until the mechanism head has been elevated to its proper position, whereupon the supporting bolts 46 are inserted to suspend the mechanism head in its operative position.

40 The same carrier brackets 130 are also used to raise the pump supporting shelf 27 with the pumps and associated apparatus mounted thereon to its proper position as shown in Figure 12.

From the foregoing description, taken in connection with the accompanying drawings, it will 45 be readily apparent to those skilled in the art, that this invention affords numerous improvements in suction sheet feeders which collectively afford greater accuracy at high speeds and greater convenience of operation.

50 What we claim as our invention is:

1. In a device of the character described, a vertically movable support for a pile of sheets, means to rapidly raise and lower the support including a power driven pinion and gears shiftable into engagement with the power driven pinion, a gear shifting member to selectively engage either of said gears with the power driven pinion, an electric motor to drive said pinion, a push button control switch for the motor, and means operable by shifting movement of the gear shifting member to depress the "stop" button of the control and thus stop the drive motor, whereby the operation of the motor requires manually holding of the "start" button down as long as raising or lowering of the pile support is to continue.

2. In a device of the character described, a vertically movable support for a pile of sheets, means driven by an electric motor to selectively raise and lower the support, a push button control for starting and stopping the motor mounted near the movable support so that the movable support is readily visible to an operator stationed at the push button control, a member movable to ren-

der the motor driven raising and lowering means operative, and means to depress and hold down the "stop" button of the control upon movement of said member to render the raising and lowering means operative, whereby the electric motor is stopped and operation thereof requires manually holding the "start" button down to thus insure the presence of the operator near the pile support.

3. In a device of the character described, a vertically movable support for a pile of sheets, means to automatically elevate the pile support, means independent of said means for automatically elevating the pile support and driven by an electric motor to selectively raise and lower the support, a manually operable member to render said independent motor driven means operative, a push button control for starting and stopping the electric motor, said push button control being located near the movable pile support, and means operable by movement of the manually operable member to render the independent pile elevating and lowering means operative to positively prevent actuation of the automatic pile elevating means and to depress the "stop" button of the control so that the running of the electric motor to effect operation of the independent raising and lowering means requires manually holding the "start" button down and thereby insures the presence of an operator near the pile support.

4. In a device of the character described, a vertically movable platform for a pile of sheets, a movable support for the platform, and means to effect sidewise adjustment of the pile comprising, spaced vertical rigidly connected rails, means connected with the platform and slidably engaging said rails, and adjusting means for shifting the connected rails sidewise.

5. In a device of the character described, a vertically movable platform to support a pile of sheets, supporting means for said platform, a barrier with which one side of the pile is engageable, said barrier including a vertical bar, means connected with the platform and slidably engaging said bar whereby the platform is guided for vertical movement by said bar, and adjusting means to shift said bar sidewise to effect sidewise adjustment of the pile.

6. In a sheet feeder of the type in which sheets are withdrawn from the top of a pile, a readily set up supporting structure, a support for the pile adjustably carried by the supporting structure and including flexible elements, and means at the top of the supporting structure to draw the flexible elements upwardly, a mechanism head adapted to be mounted at the top of the supporting structure, said mechanism head being comparatively heavy, and means attachable to certain of the flexible elements and adapted to carry the mechanism head up to its position of attachment upon drawing said flexible elements upwardly, whereby in erection the mechanism head is easily raised to its position of attachment without the aid of external hoisting mechanism.

7. In a pile type sheet feeder, a platform to hold a pile of sheets, a supporting structure, flexible elements suspending the platform from the supporting structure, a vertical guide rail, means movable with the platform and slidably fitted to the guide rail, and means for adjustably fixing the position of the guide rail to constrain the platform to vertical movement along a fixed line.

8. In a pile type sheet feeder, a vertically movable platform to support a pile of sheets, sup-

porting rails for the platform, flexible elements for suspending the supporting rails from an overhead support with the rails inclined downwardly toward the front of the feeder, rollers between the platform and the rails whereby the platform with the pile thereon moves forwardly by gravity, a plurality of vertical bars collectively forming a barrier in front of the pile and against which the pile moves by gravity, one of said bars being adjustable sidewise, and means connected with the platform and slidably fitted to said sidewise adjustable bar whereby the platform is guided for vertical movement by said bar.

9. In a sheet feeder of the type in which sheets are withdrawn from the top of the pile, a readily

15

set up supporting structure, rotatable sprocket shafts mounted on the upper portion of the supporting structure, sprocket wheels on said shafts, sprocket chains trained over the sprocket wheels, a mechanism head adapted to be mounted at the top of the supporting structure, said mechanism head being comparatively heavy, and carrier brackets attachable to the lower ends of the sprocket chains and slidably engageable with upright portions of the supporting structure to be guided thereby, whereby the mechanism head may be raised to its position of attachment by rotation of the sprocket shafts.
